[57] CLAIM

The ornamental design for a surgical clip, substantially as shown and described.

DESCRIPTION

FIG. 1 is a perspective view of a surgical clip in the open condition showing our new design;

FIG. 2 is a perspective view of a surgical clip in the closed condition showing our new design;

FIG. 3 is an end elevational view thereof, looking from the bottom of FIG. 2;

FIG. 4 is a side elevational view thereof, looking from the right of FIG. 2;

FIG. 5 is a top plan view thereof in the open condition;

FIG. 6 is an end elevational view thereof, looking from the right of FIG. 5;

FIG. 7 is a side elevational view thereof, looking from the top of FIG. 5;

FIG. 8 is a side elevational view thereof, looking from the bottom of FIG. 5;

FIG. 9 is an end elevational view thereof, looking from the left of FIG. 5; and

FIG. 10 is a bottom plan view thereof in the closed condition.
